TUNING THERMIONIC AMPLIFIER.

Application filed July 14, 1923. Serial No. 651,486.

This invention relates to radio apparatus and method, and particularly to the same for the purpose of selecting desired natural periods of the circuits of transformers employed to couple thermionic tubes or audions forming parts of a radio amplifying receiving set.

The object of the invention is to provide apparatus which will permit convenient execution of the novel method by the user, such apparatus to be of low cost and of practical, sturdy construction.

The invention consists of the apparatus and method shown and described in the accompanying drawings and following description.

Of the drawings, Figure 1 is a diagrammatic illustration of a novel form of apparatus suitable for executing the novel method; and Fig. 2 is a view of a unit panel construction embodying the essence of the invention and suitable for use as a portion of a radio amplifying receiving set, this portion comprising novel forms of transformers cooperating with suitable switching means.

A modification of the invention is shown in Figs. 3 and 4, whereof Fig. 3 is a diagram similar to Fig. 1, and Fig. 4 is a detailed view of the modified form of controlling means shown in the diagram Fig. 3.

It is now the practice, in thermionic tube amplifier receiving sets, to couple successive tubes by a transformer, such transformer and its circuits being designed to have a natural period adapted to give best results when the period of received communications is substantially the same as that of the circuits. In such apparatus, when the received communications have a substantially different period or frequency from that of the transformer circuits, the efficiency of the set is much less. It would be possible, although not practicable, to take off tap leads from portions of the secondary or primary winding of the transformer, to suitable switches, so that the period of the transformer circuits could be varied and thereby adapted to the period of the received communications, so as to maintain a constant efficiency of the system for all received frequencies. That is not desirable as a practical matter, however, on account of the difficulty of making and maintaining proper connections between such tap

leads and the secondary or primary winding of the transformer. In particular, the wire comprising the transformer secondary is usually so fine as to make it very difficult, if not impossible, to maintain the connections of the tap leads thereto in service, even after the difficult feat had been accomplished of making such connections in the first instance. Also, on account of the high frequency currents existing in the set, the capacity effects resulting therefrom in the tap leads would very seriously conflict and injuriously affect the operation of the entire apparatus.

In this invention, there may be employed coupling transformers of the ordinary type employed in thermionic amplifier sets, as above, where the two circuits have substantially the same natural period, a fine wire secondary of relatively large number of turns being wound on a laminated iron core, and a primary being wound over the secondary; or the primary could be wound first on the core and the secondary over it; or the primary and secondary could be wound side by side; and while now it is preferred to employ such iron core, it could be omitted.

In effect, this invention comprises a means for varying the effective tuning of the two like-tuned circuits of the transformer to various wave lengths (periods or frequencies) without the necessity of tuning by variation of actual inductance or capacity in either circuit of the transformer, and particularly without varying the amounts in circuit of the primary or secondary winding of the coupling transformer.

In accordance with the invention, the transformer or transformers in the set are designed, as to their primary and secondary windings, preferably to receive at maximum efficiency the highest wave length of the various receivable wave lengths of several different frequencies. For example, in the present practice of radio telephonic broadcasting, 550 meters is the highest wave length, and transformers of this invention may be designed, as to their primaries and secondaries, to receive at maximum efficiency at such wave length. The remainder of the apparatus hereof has for its purpose to reduce the effective natural period of the transformer circuits to various lower degrees of wave length, so that the set, without any

action by the operator directly on the primary or secondary of the transformer or on any tuning inductance or tuning condenser, can be adapted to receive at maximum efficiency any transmitted communication of such lower wave lengths.

Fig. 1 shows an ordinary present-day form of audion amplifier set, as well known, which is provided with the additional apparatus of this invention and comprising, for each transformer, a third or tertiary coil T^1 which is preferably stationary and closely associated with the transformer. In Fig. 1 is a transformer A, coupling a pair of audion tubes U^1 , U^2 , which, as shown, are amplifying tubes acting on received radio frequency currents. Transformer A is designed, pursuant to well-known practice, to operate with maximum efficiency at say a frequency corresponding to 550 meters, the highest present broadcasting frequency.

As shown in Fig. 1, the third coil T^1 is associated in inductive relation with transformer A, but not connected to either primary P or secondary S of transformer A. Tertiary coil T^1 is included in a circuit of its own in which is connected lead L^1 and a pivoted switch S^1 which, as indicated by the arrowhead, can make contact with successive portions of winding T^1 , so that greater or less portions of winding T^1 are included in circuit with the switch S^1 and thereby are short-circuited or "shorted".

Tertiary T^1 is closely associated with transformer A, as by winding on top of the transformer windings P, S, for example; and owing to such close association, winding T^1 acts, when shorted (and shorted portions of it act to reduce the effective inductance of the transformer, and hence reduce the effective period or tune of the transformer (and its circuits), i. e., to reduce the wave length at which the transformer acts at maximum efficiency when connected in any such receiving set or amplifier train as that shown in Fig. 1. The tertiary winding T^1 may be arranged in various relations with the windings of the transformer, provided only that it be in substantially close inductive relation therewith.

In the apparatus of Fig. 1, a third audion tube D is employed as a detector (having grid leak GL and grid condenser GC), and this third tube is coupled with the previously acting amplifier tube U^2 by a transformer B which may be a duplicate of transformer A, and having a similar primary P and secondary S. This transformer B also may be, and preferably is, provided with a tertiary winding T^2 like tertiary winding T^1 associated with transformer A; and winding T^2 may be provided with pivoted switch S^2 like S^1 for winding T^1 for the purpose of shorting portions of winding T^2 . Also the upper ends of the two tertiaries, T^1 and T^2 ,

may be connected by lead L, as shown, in cases where switches S^1 and S^2 are to be combined to operate as a unit or under one control as shown in Fig. 2. As indicated also, each of transformers A and B may be provided with a laminated iron core C.

In Fig. 2 is shown a panel or base of bakelite or other insulating material E, on which are mounted transformers A and B of Fig. 1, with iron cores C. In the case of each transformer, a primary P is wound directly on core C, a secondary S is wound over such primary, and a tertiary coil (T^1 and T^2 for the two transformers) is wound over the fine wire secondary S. In the use of the invention thus far, four turns of each tertiary coil are wound on the outside of the transformer windings. The wire for the tertiary coil is a coarse insulated wire, about No. 20 B. & S. gauge stranded or solid wire. The coils of primaries P and secondaries S may be of any design, as well known, save that they are such as to provide a natural period for the circuit corresponding with the highest wave length expected to be received. To each turn of the tertiary winding, at a bared portion thereof, is soldered a lead. In the case of the left-hand transformer, four of such leads extend to switch points 1-4, and from one end of the tertiary coil a lead L is taken which extends to a corresponding lead L extending to the end of the right-hand tertiary coil T^2 , both of which are connected by lead L^1 to the short-circuiting switch S^1 , 2. The four remaining leads from the right-hand tertiary coil T^2 extend to right-hand contacts 1-4 arranged in reverse order to contacts 1-4 of the left-hand tertiary T^1 . Switch S^1 , 2 is provided with two extensions 5, 6 which play over the respective series of contacts at left and right. Each series of contacts also includes a switch contact point 0. When switch S^1 , 2 engages contacts 0, 0, no portion of either tertiary is shorted and the influence of the tertiaries is nil, so that transformers A and B operate at their normal or natural period, i. e., preferably that of the longest wave length receivable. When the switch engages the two contacts 1, 1, one turn of each of the two tertiaries (T^1 , T^2) is shorted, so that the effective inductance of the windings of both transformers is reduced, and hence the effective periods of the transformers is reduced so that they may operate at maximum efficiency at some received wave length between say 550 meters (the highest receivable) and say 250 meters, the lowest wave length employed in present radio telephonic broadcasting. When the switch is on contacts 2, 2, and respectively on contacts 3, 3, two and three turns respectively of the two tertiaries are shorted so that the transformers act efficiently on yet lower intermediate frequencies between 130

550 meters and 250 meters. And when switch $S^1, 2$ engages contacts 4, 4, all of each tertiary is shorted to permit the transformers to act efficiently at 250 meters.

5 The unit of Fig. 2 is to be employed as a portion of a complete receiving set, base E serving as a panel, box side or subpanel, and the terminals of the primaries and secondaries of the transformers being connected in the circuits of the set as indicated in Fig. 1, and for that purpose extending to the circuits of the other apparatus inside the casing or box for the entire set. Fig. 2 shows the inside of the panel and the switch 10 located on the inside of the panel; and pursuant to common practice, a control knob (not shown) on the outside of the panel is connected to the switch mounted on the inside wall of the panel.

20 Each unit of Fig. 2 may comprise either two transformers as shown, or a single transformer, or more than two transformers, corresponding with the number of tubes used in the set, a common switch for all being provided by preference. In Fig. 1 the input is indicated at I at the left, and from the right of the diagram the usual connections are to be made to the usual batteries and indicating apparatus, such as telephones 25 or loud speakers. The tubes U^1, U^2 and D are shown by their usual conventions of grid, plate and filament, and such tube elements are to be connected in the circuits with the batteries in the well-known manner.

35 The control afforded by the execution of this method is a very perfect one, and, as indicated in Fig. 2, may be effectuated by a single controlling handle, so that the wave length of the entire set may be altered by 40 a single control. Also the construction as to the tertiary coils is very simple, practical and inexpensive.

In the modification shown in Figs. 3 and 4, a resistance R is acted on by the switching means as an alternative to the cutting in and out of portions of the tertiary by the switch. This permits a complete elimination of tap leads of Figs. 1-2 from intermediate points of the tertiaries or auxiliary inductances to the control switch, the only leads from the auxiliary inductances in this modification being from their ends to the control switch via the rheostat. In the diagram of Fig. 3, the tertiaries T^1, T^2 respectively are provided with resistances R and R^1 , and the switch $S^1, 2$ is disposed relative to said two resistances so as to act to cut them gradually in or out simultaneously. Switch $S^1, 2$ in this case is really the operating member of a rheostat. This modification is shown in detail in Fig. 4, wherein the two resistances R and R^1 and switch $S^1, 2$ are mounted on an insulating base E; thus illustrating that in any case the switch 60 and its contacts or resistances may be

mounted on a base independently of the transformers as distinguished from the form shown in Fig. 2. In Fig. 3 is shown also at X the combination in the set of a variable stabilizing resistance X in accordance with 70 my application, Serial Number 644,832, filed 12 June 1923.

As an alternative to the use of the unit panel shown in Fig. 2, the transformers may be disposed in the set in any ordinary fashion, and switch $S^1, 2$ be located at any convenient point of the panel of the set for easy control by the user; and in such cases the leads from the tertiaries to the switch may be bunched together and led through an 75 insulating tube (not shown) secured to the interior of the casing of the set. In such case (as distinguished from the case of tap leads from the secondary or primary of the transformer), there is no resulting harmful 80 action of capacity effects involved in the leads, for the reason that in the case of this invention the tertiary winding comprises only a few turns (as four shown), so that therefore the voltage from turn to turn of 85 the tertiary is quite low, on account of the large ratio between such tertiary and the transformer primary comprising, for example, 150 turns more or less. The voltage between turns of the tertiary being low, therefore 90 the voltage from tap lead to tap lead is low, thereby resulting in lack of deleterious 95 capacity effect in the leads.

In the modified form of the invention shown in Figs. 3 and 4, the ultimate operation is exactly the same as in the form of Figs. 1 and 2, in the sense that the control permits limitation of the current in the tertiary which is effective upon the transformer, i. e., in both cases the control is of 100 the ampere turns of the current induced in the winding of the tertiary by the transformer. In Figs. 3 and 4, however, the operation in detail is specifically different, in that the resistance limits or varies the 105 current flowing in the permanently completely shorted tertiary (through the resistance), so as to control the effect of the shorting winding on the effective inductance of the transformer. In both cases, the tertiary 110 is variably shorted; in the case of Figs. 1 and 2 by successively shorting different portions of the tertiary coil; and in the case of Figs. 3 and 4 by the permanent shorting of 115 the entire tertiary coil but via the variable 120 resistance by which the degree of effective shorting is continuously changed. In both cases, the ultimate result is control and variation of the effective wave length of the transformer.

In Figs. 3 and 4, the lower the resistance R in circuit with the tertiary, the shorter 125 will be the effective wave length of the transformer; because then more current is allowed to flow in the tertiary, thereby re- 130

ducting the effective inductance of the transformer and therefore reducing its effective wave length.

An advantage of the modification of Figs. 3 and 4 is not only the elimination of tap leads from transformer primary P or secondary S, but also the elimination of all intermediate tap leads from the tertiary winding. Another advantage of the modification of Figs. 3 and 4 is that, as distinguished from the step-by-step operation of Figs. 1 and 2, the resistance control affords a smooth and even change of wave length, which adapts the set to maximum efficiency for absolutely all wave lengths between the maximum and minimum receivable wave lengths. If the leads be short between the tertiary and the rheostat, the value of the resistance itself may be made very low, the total permissible value for each resistance being as low as six ohms.

In Figs. 3-4, R may be taken to illustrate an inductance coil variable by switch S¹, 2 or a variable capacity in lieu of an ohmic resistance. The employment of a variable condenser in the circuit of the shorting coil T¹ or T² permits a comparatively rough tuning of the transformer. I have found that either an inductance coil or an ohmic resistance is preferable to a condenser capacity, because they are cheaper and operate more uniformly. The addition of inductance or resistance to the circuit of the shorting coil increases the wave-length (decreases the period) of the transformer. In a case of a capacity, however, I have found, for example, as follows:—A small capacity such as .01 mfd. when included in the circuit of a shorting coil T¹ or T² reduced the transformer wave-length from 480 meters to 240 meters; a .02 mfd. capacity gave the transformer a wave-length of 270 meters; and additional capacity produced slightly increasing wave lengths. But the resistance, tuning coil and condenser are included broadly as equivalents herein as reactances generally.

If desired, in any case, the shorting winding of any embodiment of the invention may be connected to ground.

While it is preferable to employ a double-winding or inductive type of transformer as shown, yet it is permissible within the invention to employ a single coil or auto-transformer.

I claim:—

1. The means, as a unit portion of a thermionic amplifying apparatus, for simultaneously varying the effective wave-length of the circuits of a succession of transformers

which couple successive audion tubes, which tube-transformer circuits have a natural period at which a given received wave-length is efficiently received, said means comprising a panel of insulating material having 65 mounted thereon at least two of such coupling transformers; a corresponding number of auxiliary inductances arranged respectively in inductive relation with the two windings of the successive transformers but not electrically connected to either of them, whereby the effective short-circuiting of 70 said auxiliary inductances reduces the effective inductances of the windings in the successive transformers; switching means 75 also mounted on said panel; and leads between said auxiliary inductances and said switching means whereby the operation of the latter simultaneously varies the natural-wave-length circuits as to their effective 80 wave-length without variation of their natural wave-length.

2. The means for reducing the effective wave-length of both circuits of a transformer which couples a pair of audion tubes, which tube-transformer circuits have a natural wave-length receiving efficiently a high wave-length, said means comprising an inductance in close inductive relation with each of said transformer windings in the 90 two tube circuits; and means for short-circuiting more or less of said inductance, thereby reducing the effective inductance of the transformer windings and reducing the effective wave-length of said high wave- 95 length tube-transformer circuits, permitting the apparatus to receive efficiently a wave-length lower than the natural wave-length of the circuit.

3. The means for simultaneously varying 100 the effective wave-length of the circuits of a succession of transformers which successively couple successive audion tubes, which tube-transformer circuits have a natural period at which a given received wave-length 105 is efficiently received, said means comprising a number of auxiliary inductances corresponding in number with such transformers and respectively in inductive relation with the portions of the successive transformers 110 which are connected in the respective tube-circuits; a common switch; and leads between said switch and the respective auxiliary inductances, whereby the operation of the switch simultaneously varies the effective 115 inductance of the portions of the successive transformers in said circuits and therefore varies the effective wave-length of the said circuits.

WILLIAM M. BAILEY.
